7 Claims. (Cl. 114—77)

1

This invention comprises improvements in or relating to lifeboats or similar rescue devices for air and other craft.

It is an object of the invention to provide a new or improved construction which is capable of simple installation on craft to which these devices are to be applied, is readily releasable from the craft and provides a self-contained unit capable of carrying all emergency equipment while furnishing desirable accommodation for members of the crew.

According to this invention, a lifeboat or similar rescue device for an air or other craft comprises a rigid watertight container suitable for being housed at top or side of the fuselage, hull or body of the craft, and means designed to hold said container in position on the fuselage or the like but which is readily releasable, when emergency arises, so that the container may be launched or launches itself on the water.

It is advantageous to construct these devices in such a way that their outer surface merges into the skin of the fuselage, hull or other part of the craft so as to preserve, or substantially preserve, the streamline or other recognised contour thereof, and for this reason, it is preferred to construct the devices for accommodation in inverted position on the craft and associate with them means whereby they will become self-righting or can be righted as soon as they are afloat. To this end the devices may be made unbalanced, either symmetrically or asymmetrically, or provided with fittings adapted to render them so unbalanced, so that they will roll over or can be readily rolled over in the water. As an alternative, rupturable or disconnectable release means are provided between the devices and the air or other craft for causing the devices to be self-righting.

Auxiliary buoyant means are suitably associated with the devices to assist flotation or self-righting action. Thus, one or more inflatable bodies are associated with the container together with means whereby such bodies are caused to become inflated upon release of the container or when the latter has taken to the water.

The inflatable bodies may include one or more which are inflatable immediately on release of the container and operative to facilitate launching. The inflation of this body or bodies may be arranged to take place in such a manner that the effect is to propel or positively eject the container from the craft and also, if desired, to assist self-righting.

According to another arrangement, a para-

2

chute release for the container from the craft may be provided. This release could be used alternatively to any other release device if desired.

5 In any event, the container could be adapted for the stowage of various articles or commodities such as would be desirable or necessary for the welfare of those rescued. It might also contain sails, an engine or other means for propulsion.

10 It will be appreciated that a device of the nature referred to presents advantage in the embodiment of a rigid container which is accommodated in or on the fuselage or body of the craft.

15 It can readily be shaped so as to be accommodated without detriment to streamline characteristics of the craft. When launched, it is capable of providing a desirably rigid body for containing various necessities for sustenance or assistance of members of the crew. Combined with auxiliary buoyant means, such as the inflatable bodies, which may desirably have a formation and application suitable for providing the container with end or bow and stern sections, and/or means for self-righting, and/or outboard or out-rigger floats, it further enables a semi-rigid or rigid boat-like device or raft to be constructed which possesses considerably enhanced advantages from the point of view of safety and stability.

20 Moreover, it is more convenient, with the rigid container, to step a mast in the device. In order that the invention may be the more readily understood reference is directed in association with the accompanying drawings to the following description of suitable practical examples of lifeboats or similar rescue devices in accordance with the present improvements.

In the drawings—

25 Figure 1 is a general diagrammatic view of an aeroplane fitted with rescue devices of the nature forming the subject of the invention and constructed according to the example shown in Figure 2.

30 Figure 2 is a part-sectional elevation, to a larger scale than Figure 1, showing a first example of such a rescue device inverted (as compared with Figure 1) as it normally would be after launching from the aircraft.

35 Figure 3 is a part-sectional plan of Figure 2.

40 Figure 4 is a view similar to Figure 2 but taken at right-angles thereto.

45 Figures 5 and 6 are respectively part longitudinal and transverse sections of the aircraft to illustrate principally the means of attachment of the rescue device to the aircraft.

Figure 7 is a section on the line VII—VII of Figure 1.

Figure 8 is an elevation of the rescue device when fully launched and with a mast erected and a sail set.

Figure 9 is a plan of Figure 8 with the mast and sail omitted.

Figure 10 is a wiring diagram illustrating suitable electrical means for release of the rescue device from the craft to which it is attached.

Figure 11 is a diagrammatic view illustrating symmetrical and asymmetrical constructions of the bolsters for righting or inverting the rescue device on launching.

Figure 12 is a diagrammatic view illustrating the rescue device in righted condition and showing the inflatable bow and stern sections during inflation.

Figure 13 is a view showing to a larger scale the release hook seen in Figure 3.

Figure 14 being a view of the hook in released condition.

Figure 15 illustrates an aeroplane fitted with another example of rescue device in accordance with the present improvements, and

Figures 16 and 17 are transverse views of a further example of rescue device for providing accommodation in the event of non-righting of the devices on launching.

In the general view, Figure 1, the aeroplane 1 is shown ditched and in sinking condition, whilst it will be apparent from the figure that the rescue devices of the invention may be provided on the craft in various positions. There might be one aft, as at 2 for instance, and one forward, as at 3, or there might be only one of the devices mounted at 2 or 3 or other convenient place as will be understood.

In the first example, these rescue devices, as shown in Figures 1 to 7 comprise a hollow rigid container 4 of rectangular form in plan, suitably of metal, plastics or wood, and having curved or sloping sides 5 and ends 6 and a top 7 which, with the sides 5, makes the container arched or curved transversely. This container 4 is fitted to the aeroplane 1 in a recess 8 extending across the top of the fuselage and open at the top. As will be apparent, the shaping of both recess 8 and container 4 is such that the sides 5 and the upper surface 7 of the container merge into the streamline formation of the fuselage of the aeroplane 1.

The container is releasably retained in the recess 8 in the manner hereinafter described and its launching from the recess 8 should the craft 1 become ditched is assisted by inflatable bolsters 14 hereinafter described. The container is housed in the recess 8 in inverted position and the action of the bolsters 14 is to bring it, or assist in bringing it, right side up after launching. However, should the bolsters 14 fail to inflate, the container may simply float off from the sinking craft 1 and can then be brought right side up manually or otherwise.

Passing now to more detailed description, reference is directed to Figures 2 to 6, 8 and 9 of which Figures 2 to 4, 8 and 9 show the container 4 inverted as compared with Figure 1 though in the correct position after launching. In Figures 2 to 4 it will be seen that the interior of the container is divided into compartments 9, 10 and 11, shown extending longitudinally of the craft. The two outer compartments 9 and 11 are for housing miscellaneous life-saving or welfare equipment such as food, water and signalling ap-

paratus and dry clothing. The middle compartments 10 are to contain a number, say four, of carbon dioxide or other fluid pressure cylinders 12 (which could be housed so as to be capable of being jettisoned), and also other gear such as a mast, sails, oars, rudder, and so on, which may be stowed in lockers (not shown).

The fluid-pressure cylinders 12 are for the inflation of buoyant bodies attached to the container. Thus, there may be in shallow compartments 13 on the underneath of the container and transversely at each end, one of the inflatable bolsters 14 aforesaid which are suitably of segmental shape when inflated as will be understood from Figure 11. Then in compartments at the ends of the container (these compartments being defined by the vertical walls 4^a and part of the upper surface 7 of the container and covered by the ends 6 which are removably mounted), there are suitably contained two independently-inflatable sections capable of providing the container, regarded as the central section of a boat-like dinghy with bow and stern sections 150 and 160 which are shown in their inflated condition in Figures 8 and 9. These sections 150 and 160 are suitably faired off to pointed stern and bow as shown in Figure 9 and in form may be tubular, see also Figure 4. As illustrated, each section 150, 160, advantageously comprises two connected tiers of tubes somewhat of wish-bone form in plan (Figure 9) and each is preferably designed, as shown by Figure 8, to make the sections slightly rising towards bow and stern for well-known reasons.

The ends 6 of the aforesaid compartments at the ends of the container 4 could be sprung into position on the container or secured by other suitable means as will be understood.

In the first example the container 4 is secured to the aircraft at a single attachment point. Thus, a ball anchorage is provided at 15 (see Figures 5 and 6), the ball being mounted on a batten 16 which is shown secured by wing nuts 17 across a hatch opening 18 in the aircraft 1 at the bottom of the recess 8. By releasing the wing nuts and removing the batten, the opening 18 can be freed for maintenance purposes in regard to the rescue device or to serve as an emergency exit from the aircraft. The ball anchorage 15 is co-operative with a latching or retaining device 19 disposed on the container 4 (see Figures 2 to 6). This latching device 19 has an entry opening 20 for the ball 15 and may be released from the latter manually, or automatically, on ditching or immersion of the aircraft 1, to release the container from such craft. The manual release of the latching device 19 may be effected by a handle as at 25, Figures 2 and 3. Automatic release may be brought about by a solenoid operative on the latching device 19 and energized through an impact or salt-water immersion switch mounted at 24 on the container 4 (Figure 3). As will be realised all necessary parts for the release may be housed within the container 4. Thus, in addition to the latching device 19 and impact or immersion switch 24 being within the confines of the container, there is also shown housed in one of the compartments, i. e. 9, a battery 26 for energizing the said solenoid.

Having thus described the general construction of the first example of the rescue devices, its manner of operation may be indicated as follows, aided by the diagram in Figure 10 of which the electrical connections will be understood: On so-called ditching of the aircraft 1, the container

4 may be automatically released from its recess 8 in the fuselage by operation of the solenoid 21 which is actuated electrically through the impact or salt-water immersion switch 24 aforesaid. As the connection of the container 4 to the craft 1 is shown at only a single attachment point (although more could be used if desired), only one securing device 15, 19 is necessary and this would release immediately the aircraft commenced to sink, or practically so. Alternatively, the manual control by the handle 25 may be used. In either case, the release is suitably adapted also to bring about inflation of bolsters 14 from one or more of the fluid pressure cylinders 12.

These cylinders could be controlled automatically or manually. In Figure 10, a switch 22 associated with the solenoid 21 is shown for automatically controlling the circuit of the electrical control valves 27 and 31 of cylinders 12. Manual control by the handle 25 could be through a connection or connections as at 25^a (Figure 3). Valve 31, however, is further controlled by a switch 30 referred to below. The bolsters 14, are under control of valve or valves 27 and, in inflating, erect themselves in planes which are normal to the plane of the container 4, see Figure 12, and blow or impel the container 4 free from its recess 8 in the fuselage, so that altogether its freeing from the craft 1, on ditching, is very reliable. The freeing is also favoured by the sloping ends 6 of the container. These also minimise risk of the container jamming from distortion of the fuselage of the craft 1 on ditching. The bolsters 14 are designed to make the container unstable as soon as they inflate so that as soon as the container floats in the water it rolls over as depicted by the arrow in Figure 11 for example. Or such design of the bolsters enables the container to be easily turned over with manual assistance or even to initiate rolling over of the container before it touches the water. The hollow rigid container 4 thus comes to a position indicated by Figure 12 to form the basis of a lifeboat or similar device. Subsequently, the bolsters 14 may be removed and for this purpose detachable connections for them with the container 4, such as press-button fastenings, may be provided at the places indicated at 28 in Figure 3. When taken off they may be placed along the sides of the container outboard and secured in position (as at 29 Figure 9). The recesses 13 for the bolsters may have detachable lids which blow off when the bolsters are inflated.

It is not until the container has been rolled or turned over as stated that the stern and bow sections 150 and 160 are inflated from one or more of the fluid pressure cylinders 12. Suitable means for bringing about this inflation comprises the aforesaid switch 30 which is shown of the mercury type comprising a closed-ended non-conducting tube 30^a, e. g. of glass, containing a drop of mercury 30^b and having two wire contacts 30^c fused or sealed into one end and separated by a small gap which is bridged by the mercury 30^b when this end is lowest. This switch 30 closes on the roll-over movement of the container and, as shown by Figure 10, is used in the circuit of the control valve 31 of one of the fluid pressure cylinders 12 and in series with the switch 22. The inflation would first blow off the ends 6 covering the aforesaid compartments for the collapsed bow and stern sections, as indicated in Figure 12, whereafter the sections would extend to the form shown in Figures 8 and 9. The inflation having been completed, the device is ready for occupation, and

is shown occupied in Figure 8. It will be realised that as the switch 30 is not effective unless immersion switch 24 is closed, any aerobatics to which the aircraft may be subjected in flight and during which the container 4 may become inverted, will not cause unintentional inflation of the bow and stern sections 150 and 160.

The crew would ordinarily abandon the aircraft 1 by the aforesaid hatch 18 in the bottom of the container recess 8 of the craft, though of course use could be made of a hatch elsewhere. The centre compartments 10 of the container 4 have a removable cover 32, Figures 2 to 4, and when the crew are aboard, this can be lifted out giving access to such gear as mast and sails aforesaid. The space thus made available provides a well for the crew who can sit in the well (see Figure 8), or along the top sides of the container which provide rigid seats, with their feet in the well; or as also indicated in Figure 8 they may sit within or upon the bow and stern sections, which suitably comprise flat floor members 33 (Figure 9) of rubberised fabric or of other flexible material situated within the confines of the inflatable tubes of these sections and secured at their edges to such tubes and to the container 4. When the well provided by the open compartments 10, is open access is also possible to the other equipment above referred to. The bottom of the well is rigid, and is shown with means at either end, at 34, for the stepping of the mast 35, which is shown erected in Figure 8 and carrying a sail 36. The well may be fitted with a keel or keels at 37, Figures 8 and 9, which may be retracted when not in use within a hollow wall or partition 38 in the well (see also Figures 3 and 4). A rudder is shown in conventional fashion in Figures 8 and 9 attached to the point of the inflatable stern section 160. Alternatively, the rudder may be attached to the opposite section 150.

The buoyancy system described would provide four independent inflatable bodies or compartments, i. e. 14, 14, 150 and 160 the inflation system at one end of the boat being a duplicate of that at the other end as shown. If the system 150 or 160 at either end should be damaged beyond repair, say on ditching or from other cause, that one could be cut adrift and the mast 35, if necessary, stepped at the other end of the container. In the unlikely event of failure of both bow and stern systems 150 and 160, the container 4 itself could still be used as a well equipped raft, and the mast, which may be telescopic as shown in Figure 8, be stepped for wireless purposes. The container would still be self-righting owing to the bolsters 14 or could be made so by using emergency bolsters similarly mounted and adapted to be inflated from the fluid-pressure cylinders 12, or by other means. The pressure fluid for inflation of the bolsters and so on, is led to the point of use in suitable manner as by pipes indicated at 39^a and 39^b in Figures 3 and 4. The arrowed ends of the leads from the battery 26 in Figure 10 are intended to indicate that the battery may also be used to supply other services such as lights or wireless apparatus.

Among the advantages of the construction of rescue device thus described are that all requisite gear is stowable internally and in such a manner as also to be available when the device is afloat, a considerable simplification of the aircraft installation is possible, and there is favourably positive release of the device from the aircraft, and minimisation of risk of inadvertent release. Moreover, inflation of the bow and stern sections

right side up is ensured, rigid foundation **4** is provided for mast and rigging, the device is more suitable for use by an inexperienced crew than known devices, and maintenance of the complete unit can be done away from the aircraft.

As already indicated, in the event of failure of the operating gear for inflating the bolsters **14**, the container **4** will float off the aircraft when the latter sinks and the container is released at **15**. In order to accommodate such a case a further means of righting the container may be provided and is shown as comprising ties **41** embodying weak links or other means of disconnection designed to break or be released when the container has rolled over to a predetermined angle, the ties connecting the aircraft **1** on either side to points on the top of the container **4**, see Figures 3 and 6. The connection to the aircraft at **50** is a fixed one but for connection to the container **4** use is made of swivelling hooks **71** mounted on a base **43** secured to the container having a resilient projection **49**, Figures 3, 6 and 13. On sinking of the aircraft and after release at **15** either tie can be caused to draw down the container on one side and so roll it over. The other tie, of course, would be required to be disconnected from its hook **71** to enable the rolling over to take place and this can be done by the operator of the device, prior to ditching, by pulling a handle such as **48**, Figure 3, and so withdrawing a retaining pin **45** for the hook through a control line **47**. The hook will then take up the position shown in Figure 14, in which position the ring **46** of the tie **41** can pull out past the resilient projection **49** and thus will be incapable of exercising any restraint. On the other hand, the ring **46** of the first tie will not pull out past the resilient projection **49** of its hook **71** until the latter (still retained by its pin **45**) comes to a more or less vertical position at which stage, of course, the rolling over of the container has been fully initiated. By this arrangement, the container **4** on release may roll over on either side of the aircraft **1** at will, to cause launching of the rescue device on the one side or the other of the aircraft if so desired for reasons of weather or damage to the craft. The ends **50** for anchoring the ties **41** to the craft **1** are, of course, shown loose in Figure 3. They are shown in secured positions in Figure 6.

In order to prevent premature or accidental operation of manual control parts of the rescue devices, readily detachable guards such as the one shown at **51**, applied over the container-release handle **25** in Figure 5, may be employed to isolate or cover these parts.

According to a modification, instead of automatic release of the container **4** from the recess **8** of the aircraft **1** being controlled by an impact or immersion switch disposed on the container at **24**, a similar switch could be mounted at the bottom of the fuselage as shown at **23** in Figure 1. This arrangement would provide for release of the container at **15** immediately the craft touches the water. As a further modification the switches at both **23** and **24** may be used, though this, though preferable, is not essential as the single switch at either location would be sufficient.

According to another modification, which is illustrated by Figure 11, the bolsters may be constructed asymmetrically, as indicated by the dot-and-dash line at **14^a**, instead of symmetrically as shown by the full line at **14**, so as to cause release of the container on a predetermined side of the aircraft, or to make the device roll over

in a particular direction when launching it from the aircraft.

By a further modification, the bolsters **14** or **14^a**, instead of being detachable from the container **4** as aforesaid may be fixed to the container and thus be kept in their original position, after launching of the container, to provide self-righting characteristics.

As another modification, arrangement may be made whereby the bolsters **14**, **14^a**, when detachable, may after launching be fitted on outriggers to increase lateral stability of the container in the water.

According to another modification, the cover **32** of the middle compartments **10** of the container **4** may be used as a centre board or keel at **37** in Figures 8 and 9. The quick-release device **19**, Figures 2 to 4, would then be made removable to allow entry of the cover **32** into the hollow wall or partition **38**. If no keel or centre board be used, the part **38** may be omitted so that the two compartments **10** would then be merged in one single compartment of the container.

By another modification the top **7** of the container **4** may be provided with emergency openings, as at **40** in Figure 3, to give access to rations and other vital stores in the compartments **9**, **10** and **11**, in the unlikely event of failure of the pressure-fluid systems and of the crew being too weak to overturn the container themselves.

For a similar reason, any enclosed devices in the compartments **9**, **10** and **11** of the container, such as an enclosed radio set **52**, or water tanks **53** (Figures 3 and 8), may be made accessible whenever side up the container **4** is when released.

As a modification, if the capacity of the craft were required to be greater than that of the first example, the number of inflatable tubes in the bow and stern sections **150**, **160** would suitably be increased, e. g. to three at each end.

An outboard engine, may also be used in the first example if desired. This engine may have alternative mountings at either end of the container, like the mast **35** aforesaid and for a similar reason, and the container in each case provides a rigid foundation for the mounting of the engine.

The example of rescue device illustrated by Figure 15, is designed for more ready escape of the crew from aircraft and without the disadvantages of immersion. It is also more suitable for use by inexperienced personnel such as passengers.

According to the example of rescue device, illustrated by Figure 15, the container **4** is adapted to be pulled off an aircraft in flight by means of a parachute **58**. The fuselage of the aircraft **1** might have a rearward top-side step **59** and a recess or compartment be provided for the container to the rear of the step so that the streamline characteristics of the craft are substantially retained. The parachute apparatus, suitably including a pilot parachute **60**, could be accommodated in a rear compartment **61**, of the container.

Occupants of the aircraft, on emergency, would enter the appropriately sized container before its release from the aircraft and take up a lying down position in compartments or spaces of the container such as indicated in diagrammatic fashion in the drawing, a cover similar to **32** aforesaid being removed after launching.

As will be realised, the parachute **58** would draw the container away from the craft **1** sub-

stantially in its own plane, so that launching is effected with desirable facility.

The small compartment marked 13 in Figure 15 is to contain an inflatable bow or stern section such as 150 and 160 aforesaid. In general it is not essential to have such inflatable sections at both ends of the container and Figure 15 is an example where there is one at only one end.

In this example escape at night would be rendered safer as any uncertainty as to whether the aircraft was over land or water would be immaterial. If the aircraft were out of control, on fire, or uncertain of its position, the parachute would therefore be used. The occupants could release the parachute from the container, after use, in any suitable manner as will be understood. On the other hand, if the captain of the aircraft decided that he could more successfully save his crew or passengers by ditching or forced landing the lifeboat could be available in the same manner as in the first example. The ditching stations provided would, in the latter case, be equally suitable as crash stations.

In known aircraft, abandoning by parachute over the sea is open to the great objection of dispersal of the crew or other personnel being unavoidable with consequent lowering of morale, high exposure risk and difficulty of search, and this can be avoided by this example of the invention.

The container in Figure 15 is shown with transverse stowage compartments 56 fore and aft for equipment, food supplies and so on.

According to a further example of construction, the rigid top or rigid top and sides of the container of construction already described may further provide for fitting of one or more collapsible keels so designed as to provide greater safety of the crew or other occupants and a safe location for such emergency equipment as the crew would require to be immediately available in the event of failure of the self-righting gear and the crew being too exhausted to right the boat manually. For instance, as shown by Figure 16 two keels 62 may be hingedly mounted at each side of the central wall 10 to be collapsible into a recessed formation 63 on the outside of the rigid top (or rather the bottom as shown because the container is inverted). These keels, if the container were not righted, could be swung upwardly and outwardly to form a space 64 for emergency equipment as illustrated by Figure 17. There might be removable covers like 40 aforesaid or doors 65 in the recessed part 63 to allow access to the well 10 and the keels would be supported by struts 66 in the upswung position.

It will be apparent that the invention is not restricted to the examples of construction thus particularly described but that other modifications are possible without departing from the broad scope and intention of these improvements. It is considered, for example, that like apparatus might, with advantage, also be incorporated in similar fashion, in the hulls of submarines or other marine vessels for use on sinking of these vessels.

The invention includes within its purview and in combination not only lifeboats and similar rescue devices of the new or improved construction described, but also such modification or construction of air or other craft, as would be requisite or advantageous to make provision for the recess or compartment, such as 8, to accommodate the devices, and this suitably with-

out, or substantially without, sacrifice of stream-line or contour characteristics of the craft.

I claim:

1. A lifeboat or similar rescue device for an air or other craft, comprising a rigid watertight container to be housed on said craft, means on said container operative to hold it in position on said craft but which is readily releasable, when emergency arises, so that said container may

10 launch on water, inflatable buoyant means attached to and adapted to be housed in uninflated condition in said container, said inflatable buoyant means having a form such that when inflated it presents lines which extend in faired fashion from and substantially merge into the lines of the container and bounds with the container a space, a sheet of flexible material secured to, and extensible on inflation of, said inflatable buoyant means to provide a floor for said space to enable 15 the latter to accommodate occupants of said device, and means for inflating said inflatable buoyant means and projecting the same from its housing in the container when the latter is released from said craft.

2. A lifeboat or similar rescue device for an air or other craft comprising a rigid watertight container of substantially rectangular form in plan to be housed on said craft, means on said container operative to hold it in position on said 20 craft but which is readily releasable, when emergency arises, so that said container may launch on water, inflatable buoyant means attached to opposite ends of said container, said inflatable buoyant means having a form such that when

30 inflated it forms bow and stern sections the lines of which extend in faired fashion form and substantially merge into the lines of opposite sides of said container and each of which sections bounds with the container a space, sheets 35 of flexible material secured to, and extensible on inflation of, said inflatable buoyant means to provide a floor for said spaces to enable the latter to accommodate occupants of said device, and means for inflating said inflatable buoyant 40 means and projecting the same from its housing in the container when the latter is released from said craft.

3. A lifeboat or similar rescue device for an air or other craft, comprising a rigid watertight 45 container to be housed in inverted position on said craft, means on said container operative to hold it in position on said craft but which is readily releasable, when emergency arises, so that said container may launch on water, inflatable

50 buoyant means attached to and adapted to be housed in uninflated condition in said container, means for inflating said inflatable buoyant means and projecting the same from its housing in the container when the latter is released from said craft so as to assist flotation of the rescue device

55 on said water, inflatable bolsters of substantially segmental shape when inflated and which when inflated project from the container in planes which are normal to the plane of the container, these bolsters being attached to and adapted to be housed in uninflated condition in said container, and means for inflating said bolsters and projecting the same from their housing in the container when the latter is released from said

60 craft, the construction of the bolsters being such as when inflated to propel or positively eject the container from said craft and to serve in turning said container over to come right-side-up on said water.

75 4. In combination, an air or other craft and

11

a lifeboat or similar rescue device therefor, such device comprising a rigid watertight container to be fitted into a recess of said craft, means on said container and in said recess operative to hold the container in position in the recess, said means being readily releasable, when emergency arises, so that said container may launch on water, inflatable buoyant means attached to and adapted to be housed in uninflated condition in said container, said inflatable buoyant means having a form such that when inflated it presents lines which extend in faired fashion from and substantially merge into the lines of the container and bounds with the container a space, a sheet of flexible material secured to, and extensible on inflation of, said inflatable buoyant means to provide a floor for said space to enable the latter to accommodate occupants of said device, and means for inflating said inflatable buoyant means and projecting the same from their housing in the container when the latter is released from said recess.

5. A lifeboat or similar rescue device according to claim 1, wherein the rigid watertight container is constructed for accommodation in inverted position on said craft, and the device includes means for righting said container as soon as it is afloat, and a plurality of collapsible keels on said container and designed to provide accommodation for occupants and equipment in the event of the container happening to remain unrighted on launching.

6. A lifeboat or similar rescue device according to claim 1, wherein the container is adapted to be housed in inverted position on the air or other craft, means further being provided for bringing the container to right-side-up position when released from said craft and the means for inflat-

12

ing the said inflatable buoyant means and protecting the same from its housing in said container being operative to effect such inflation after the container is in such right-side-up position on the water.

10 7. A lifeboat or similar rescue device according to claim 1, wherein the rigid watertight container is housed on said craft in a substantially horizontal position, and the device includes a parachute associated with said container and operative to withdraw it substantially in its own plane from said craft upon release of the container.

BASIL WILMOT OLIVER TOWNSHEND.
